DESIGN FOR A CHEEK STRAP

Jesse D. Padgett, Dallas, Tex.

Application June 10, 1943, Serial No. 110,422

Term of patent 14 years

To all whom it may concern:

Be it known that I, Jesse D. Padgett, a citizen of the United States and a resident of Dallas, in the county of Dallas and State of Texas, have invented a new, original, and ornamental Design for a Cheek Strap, of which the following is a specification, reference is had to the accompanying drawing, forming part thereof, in which:

Fig. 1 is a front plan view of a cheek strap showing my new design.

Fig. 2 is a bottom plan view of the same.
Fig. 3 is a longitudinal side view of the strap.
Fig. 4 is a cross sectional view on line 4—4 of Fig. 1.

I claim:
The ornamental design for a cheek strap, as shown.

JESSE D. PADGITT.
